Inventor,
Eric Lindholm

ERIC LINDHOLM, OF BROOKLYN, NEW YORK.

Letters Patent No. 91,755, dated June 22, 1869.

IMPROVEMENT IN GUIDE-ROLLING HOOP.

The Schedule referred to in these Letters Patent and making part of the same.

To all whom it may concern:

Be it known that I, ERIC LINDHOLM, of Brooklyn, Kings county, and State of New York, have invented an Improved Rolling-Hoop, or toy for children; and do hereby declare that the following is a full, clear, and exact description thereof, reference being had to the accompanying drawings, making part of this specification, of which—

Figure 1 represents an elevation;

Figure 2, a top view; and

Figure 3, a top view of the guide, detached from the hoop.

This invention relates to a guide-rolling hoop for young children who are not grown, or sufficiently dexterous to manage a rolling-hoop with a stick or beater; and

It consists of an ordinary rolling-hoop, to which is attached a guide, said guide consisting of a handle, (which is held by the child,) having a slotted spring-clasp, which embraces the hoop, and through which the hoop revolves, by means of which the child is enabled to roll the hoop along in a vertical position, and direct its course, and, when desired, can detach the

guide and use the same as a beater, as the grown children do.

In the drawings—

A indicates the hoop.

B, the guide, which consists of the handle, C, and spring-clasp, D, having circular openings, *d d*, through which the hoop revolves as the same is pushed along by the child holding the handle.

This guide is capable of being sprung on, and in like manner detached from the hoop, as represented in fig. 3, for the purpose stated.

I do not claim a trundling-guide, embracing the hoop.

What I claim as my invention, and desire to secure by Letters Patent, is—

The construction of the guide B, with curved spring-clasp D, having free openings *d d* at the ends, while the elastic middle portion thereof retains the hoop in the guide, substantially as herein specified.

In testimony whereof, I have hereunto set my signature, this 29th day of September, A. D. 1868.

Witnesses:

A. NEILL,

ARTHUR B. WILLIAMS.
